UNITED STATES PATENT OFFICE.

GABRIEL WERNITZ, OF PLACERVILLE, CALIFORNIA.

CANDLESTICK.

SPECIFICATION forming part of Letters Patent No. 395,097, dated December 25, 1888.

Application filed June 14, 1888. Serial No. 277,144. (No model.)

To all whom it may concern:

Be it known that I, GABRIEL WERNITZ, of Placerville, El Dorado county, State of California, have invented an Improvement in 5 Miners' Candlesticks; and I hereby declare the following to be a full, clear, and exact description of the same.

My invention relates to certain improvements in that class of devices known as 10 "miners' candlesticks."

It consists in the constructions and combinations of parts which I shall hereinafter fully describe and claim.

Referring to the accompanying drawings 15 for a more complete explanation of my invention, Figure 1 is a view showing the device complete with the parts in position for use. Fig. 2 shows the handle, spear, and socket separated from each other. Fig. 3 20 shows the parts packed together for transportation.

A is the handle portion, which is bent around into the form of a ring, the two ends being extended parallel with each other, as 25 shown at B. The inner adjacent faces of the two sides B are channeled in V form, so that as they lie together the channels form a square or diamond shape in cross-section, into which the correspondingly-shaped inner end or 30 shank, C, of the spear D will slide and fit. The hole E is made through one of the sides B, and a corresponding notch, F, is formed in the shank C of the spear, so that a transverse pin or key passing through will hold the spear 35 firmly in place between the two sides B. In the present case I have shown this key G as extended upward so as to form the hook H, by which the device may be hung up whenever it is more convenient to secure it in this manner than by striking the spear into a wooden 40 beam.

I is a tubular socket in which the candle is held. This socket is made of spring-steel 45 bent into cylindrical form and having a projecting thumb-piece, J, upon one side, by which it may be sprung open sufficiently to admit a candle. This socket may either be secured permanently on the side of one of the extensions B, or, as shown in the present 50 case, it may be provided with lugs K, which extend down through one of the sides B,

passing through the V-shaped channel in that side, and having notches cut in them, as shown at L, so that when the spear-shank is inserted into its place between the two sides 55 B it will engage these notches L, and thus lock the candle-holder lugs firmly in place.

The hook H, having been inserted into the slot before described, will lock the spear in place, and the whole will be firmly held together. The length of the candle-socket is such that if the candle becomes broken it may be so placed in the socket that the broken place will be held within the length of the socket, and thus keep it in place until the 65 candle is burned down to this point, and so prevent waste.

In order to prevent danger from accident, I employ an automatic extinguisher, which consists of a disk, M, secured to the end of 70 the arm N, which is attached to or forms an extension of the spring O, having a central hub, P, which fits over the square shank of the hook. The disk is drawn back when the candle is introduced into the socket, and its 75 edge then rests against the side of the candle, the pressure of the spring being sufficient to hold it in this position with considerable force. When the candle has burned down to the disk, the latter will be forced 80 across the candle, thus cutting it off and extinguishing it, so as to prevent accident. By this construction of the jointed and detachable spear I am enabled to make a candlestick of greater length, so that there is not so 85 much danger of the candle igniting dry wood which may be near it, and when it is desired to carry it away, it is easily separated by removing the key, the extinguishing-disk, and reversing the spear, placing the hook and 90 disk upon the handle and holder, as shown in Fig. 3.

When everything is conveniently packed up, it can be put into the pocket and carried away.

Having thus described my invention, what I claim as new, and desire to secure by Letters Patent, is—

1. The handle having extensions B with a slot rectangular in cross-section, in combination with the spear having the shank fitted to the slot and the transverse locking-key

passing through the slot in one of the extensions, so as to engage the notch in the shank of the spear, substantially as herein described.

2. The combination of the handle having 5 parallel extensions B with the longitudinal slots in their meeting faces, a candle holder or socket fitted to one of the extensions, the spear having the shank fitted to said slots, a key by which the spear is locked in place, 10 and a hook formed on an extension of the key, substantially as herein described.

3. The handle having the parallel slotted extension, the candle holder or socket having lugs passing through holes in one of the ex-

tensions B and notched so as to be locked in 15 place by the shank of the spear, the transverse key by which the spear-shank is locked in place, a hook formed on an extension of the key, by which to hang the device, a disk, and a coil-spring and hub fixed to the hook-extension, so as to act as an extinguisher, substantially as herein described. 20

In witness whereof I have hereunto set my hand.

GABRIEL WERTZ.
